Marvin L. Caleiro.

UNITED STATES PATENT OFFICE.

JOHN E. THOMAS, OF BROOKLYN, NEW YORK.

FEATHERING PROPELLER.

Application filed February 28, 1922. Serial No. 539,813.

To all whom it may concern:

Be it known that I, JOHN E. THOMAS, a citizen of the United States, residing at Brooklyn, in the county of Kings and State 5 of New York, have invented certain new and useful Improvements in Feathering Propellers, of which the following is a specification.

This invention relates to propellers and 10 more particularly to that type of propeller for use in connection with airships and the like.

The principal object of the invention is to provide an aerial propeller with blades 15 arranged to partially turn or feather during use.

Another object resides in the provision of means for adjusting the degree of angularity of the blades.

20 These and other like objects are attained by the novel construction, arrangement and combination of parts hereinafter described and shown in the accompanying drawings, forming part of this disclosure, and in 25 which:—

Figure 1 is a fragmentary longitudinal sectional view of the fuselage of an aeroplane, showing an embodiment of the propeller and its associated parts.

30 Figure 2 is an enlarged sectional view taken on line 2—2 of Figure 1.

Figure 3 is a similar view taken longitudinally of the propeller.

Figure 4 is a front elevational view of the 35 feathering cam.

Figure 5 is an edge view of the same.

Figure 6 is a view similar to Figure 5 taken in a different plane.

Figure 7 is another like view taken in 40 plane variant from Figures 5 and 6.

In the drawings, the numeral 10 designates the fuselage of an airship provided with a seat 11 for an operator, and with a motor 12.

45 The fuselage has the usual radiator 13 thru which the propeller shaft 14 extends, the same being rotatably mounted in a sleeve 15 secured to the forward end of the crank case of the motor 12.

50 The rectangular end 16 of the motor shaft is adapted to fit in a conforming opening 17

formed in the hub of a dished plate 18, constituting the driving element of the propeller.

Mounted to slide longitudinally on the 55 sleeve 15 is an outer sleeve 19 carrying at its outer end a fixed cam 20, its periphery being grooved as at 21.

As illustrated, the sleeve 19 is sufficiently long to project thru the radiator, partially 60 into the fuselage, and secured adjacent its inner end is a collar 22 provided with spaced annular flanges between which is received the forked end of a lever 23.

Said lever is pivotally mounted within the 65 fuselage and is connected, by a rod 24, to a hand lever 25 mounted near the operator's seat 11.

Rotatably mounted near the forward end of the sleeve 19 is a spider or frame 26, its 70 outer or forward side being bolted or otherwise secured, as at 27, to the plate 18.

The edge of the spider is provided with an annular flange or rim 28 having, at spaced intervals, radial openings which 75 align with similar openings in the inner flange 29 to provide bearings for the blade spindles 30.

Said spindles carry at their outer ends, the blades 31 and at their inner ends have 80 cranks 32 provided with rollers 33 for engagement in the cam grooves 21, entrance or removal being effected by removal of the plate 34 as shown in Figure 4.

In operation it will be seen that as the 85 shaft 14 turns, the plate 18 will cause the spider 26 to rotate, thus carrying the blades around and causing the rollers 33 to travel in the path of the cam groove 21, thereby partially rotating the blades upon the axis 90 of their spindles 30 and giving them a feathering motion.

Obviously by shifting the sleeve 19 lengthwise the degree of angularity of the blades 31 may be varied to meet requirements.

While the foregoing describes the preferred embodiment of the invention, it is to be understood that minor changes in construction may be made without departing 100 from the scope of the invention.

Having thus described my invention, what

I claim as new and desire to secure by Letters Patent, is:—

A propeller comprising a spider, a plurality of longitudinally rotatable blades radiating from said spider, a cam having a peripheral groove, means for moving said cam longitudinally on its bearing, transversely of said blades, and cranks on the inner ends

of said blades actuated by said cam, a slideable cam associated with said spider, and means 10 carried by each of said blades co-operating with said cam for turning said blades on their longitudinal axis during rotation of the propeller.

In witness whereof I affix my signature. 15
JOHN E. THOMAS.
